INVENTOR.
HARRY W. RUBY.

BY

Emerson
ATTORNEY.

UNITED STATES PATENT OFFICE.

HARRY W. RUBY, OF SPRINGFIELD, OHIO.

CUT-OUT.

Application filed October 30, 1920. Serial No. 420,609.

To all whom it may concern:

Be it known that I, HARRY W. RUBY, a citizen of the United States, residing at Springfield, in the county of Clark and State of Ohio, have invented certain new and useful Improvements in Cut-Outs, of which the following is a specification, reference being had therein to the accompanying drawing.

10 This invention relates to a cut-out for the exhaust of an internal combustion engine and is designed more particularly for use with automobiles and the like.

15 The object of the invention is to provide a cut-out of this kind which will be very simple in its construction and easily operated.

20 A further object of the invention is to provide such a device in which it will not be necessary to use springs to control the valve, as the springs are seriously affected by the heat from the exhaust; and to this end it is a further object of the invention to provide such a device with a gravity valve.

25 A further object of the invention is to so mount the valve that when it is moved to its open position it will not only open the supplemental outlet but will be moved to such a position that it will partially 30 obstruct the flow of the exhaust gases to the normal outlet and thus divert the same through the supplemental outlet.

35 A further object of the invention is to provide means for securing the valve in its closed position so that it will not rattle or chatter.

40 A further object of the invention is to provide such a device in which the valve and its seat will be readily accessible for cleaning, or other purposes.

Further objects of the invention will appear as the device is described in detail.

In the accompanying drawings Fig. 1 is a sectional view taken longitudinally of a 45 cut-out embodying my invention; Fig. 2 is an end elevation of such a cut-out; and Fig. 3 is a side elevation of a modified form of the cut-out.

50 In these drawings I have illustrated one embodiment of my invention, with a slight modification thereof. In both forms illustrated the device comprises a tubular body adapted to be connected in the exhaust line of an internal combustion engine and having a supplemental outlet which is closed by a gravity valve, that is, a valve which will

be seated either by its own weight or by auxiliary weights connected therewith. This valve is arranged within the body of the cut-out and is supported in such a manner that when moved to its open position it will be positioned in the normal path of the exhaust gases near the normal outlet of the body and will thus divert the gases through the supplemental outlet, or cut-out opening. 60 In both forms the valve is provided with a stem which extends through the supplemental opening and is mounted exteriorly of the body. Preferably this stem is in the form of a lever which is pivotally mounted and 70 which may be acted upon by suitable operating device to move the valve into its open position. In one form of the device it is provided with a gravity lock to secure the valve in its closed position, the operating device being of such a character that it will first move the lock to its inoperative position and then open the valve. It will be understood, however, that the particular 75 forms of the cut-out here shown have been 80 chosen for the purpose of illustration only and that the device may take various forms without departing from the spirit of the invention.

In both embodiments of the invention 85 here illustrated the cut-out comprises a tubular body 1 adapted to be connected in the exhaust line. It is preferably, but not necessarily, in the form of an attachment to be applied to the exhaust pipe after the latter 90 has been installed, and, as here shown, it is capable of being applied to the exhaust line at any time. To this end the body is substantially cylindrical in shape and is open at both ends to permit the pipe to be inserted therein, as shown at 2. The body 95 may be conveniently applied to the exhaust pipe by clamping and I have here shown the body as divided longitudinally into two parts, which parts are provided with co-operating apertured lugs 3 to receive bolts 4 which serve to connect the two parts of the body one to the other and to clamp the same onto the exhaust pipe, which has an opening therein. The body is provided with a supplemental, or cut-out, opening which is preferably formed in the bottom wall thereof in line with an opening in the exhaust pipe, and, as here shown, is surrounded by a downwardly converging flange 105 5 which forms a valve seat to receive the valve 6. The valve 6, as has been stated,

is preferably a gravity valve and, as here shown, is arranged within the body and adapted to engage the converging flange forming the valve seat and thus close the supplemental, or cut-out, outlet. The weight necessary to hold the valve firmly on its seat may be imparted thereto either by forming the valve itself of a sufficiently heavy construction or by the use of auxiliary weights. The valve preferably comprises a rounded head portion which will engage the valve seat with a relatively narrow surface of contact and which will lie within the recess formed by the depending flanges and will thus be positioned out of the path of the exhaust gases as they pass through the exhaust line normally, so that the valve will offer no obstruction to the normal movement of the exhaust gases. The valve has connected therewith a stem 7 which extends through the outlet opening and is movably mounted exteriorly of the body of the cut-out in such a manner that the valve can be moved into and out of engagement with its valve seat. Further, the manner of mounting the valve stem is such that when the valve is moved out of engagement with its valve seat it will be moved into a position adjacent to the normal outlet of the body of the cut-out and will thus lie in the path of the exhaust gases and will tend to divert the same through the supplemental outlet, the valve shown in Figs. 1 and 2 having the stem 7 flattened and widened adjacent thereto, as shown at 7^a, to further obstruct the flow of the gases. Preferably the valve stem is pivotally mounted and, as shown in Figs. 1 and 2, it is in the form of an arm, or lever, which extends downwardly for some distance below the supplemental outlet, and then extends upwardly and rearwardly, that is, in the direction of the normal flow of the exhaust gases. This lever, or valve stem, is pivotally mounted near its rear end on brackets 8 carried by the body, the end of the lever preferably extending between the two brackets and being mounted upon a pin 9 which extends through the brackets. The shape of the lever and the location of its axis are such that when the lever is rocked about its axis the valve will be moved into the position shown in dotted lines in Fig. 1. The valve may be operated in any suitable manner but I prefer to operate it by means of a cable extending therefrom to the point from which the cut-out is to be controlled, such as the instrument board of an automobile.

Some means must be provided to prevent the valve from rattling or chattering due to the vibration of the machine or to the action of the exhaust on the valve. This may, in some cases, be accomplished by providing the valve with sufficient weight to hold it firmly on its seat under all operative

conditions, but in other cases this is not desirable and I have, therefore, shown in Figs. 1 and 2 a locking device for positively securing the valve in its closed position. This locking device may take various forms but is preferably of such a character that it will move by gravity into its locking position and is so connected with the operating device for the valve that the locking device will be first moved into an inoperative position and the valve then moved into its open position. The locking device may take various forms but as shown in Figs. 1 and 2 it comprises a locking member, or arm, 10, which is pivotally mounted on the body, or main casing, of the cut-out, preferably on the arms 8 between the axis of the valve stem and the body of the cut-out. The outer, or free, end of the locking arm is bifurcated and the bifurcated portions 11 thereof extend on opposite sides of the valve stem 7. These bifurcated portions of the arm are preferably curved outwardly and spaced apart such a distance that when the locking arm is moved into a position adjacent to the cut-out opening the two parts of the arm will lie on opposite sides of that opening and will not interfere with the passage of the exhaust gases therethrough. The outer, or bifurcated, portion of the locking arm is of such weight as to insure the movement of the locking device by gravity into its locking position. The locking arm has a part adapted to engage the valve stem 7 when the locking device is in its operative, or locking, position, and, as here shown, this part comprises the end of the body portion of the arm, which lies between the bifurcated portions 11 thereof, as shown at 12, and the valve stem is provided with a portion, such as a lug, or shoulder, 13 with which the part 12 of the locking arm engages when the valve is seated and the locking arm is in its operative position. The locking arm also has a part to engage the valve stem and impart upward movement thereto after the locking arm has been moved far enough to clear the part 13 of the valve stem. As here shown, this part comprises a cross bar 14 extending between the two bifurcated portions 11 of the locking arm and spaced below the valve stem such a distance that it will not engage the latter until the locking arm has been moved to an inoperative position. The operating device for the cut-out is preferably connected with the locking device and, as here shown, comprises a cable 15 connected with one of the bifurcated portions 11 of the locking arm. It will be apparent, therefore, that when the operating device, or cable, 15 is actuated the locking arm will first be moved into an inoperative position and the cross bar 14 will then pick up the valve stem and move the valve into its open position.

tion, as shown in dotted lines in Fig. 1. When the operating device is released the valve and locking arm will move downward by gravity and the weight of the locking device will assist in moving the valve firmly into a tightly closed position and when the valve has been moved into a tightly closed position the part 12 of the locking arm will engage the part 13 of the valve stem to 10 positively hold the valve in its closed position.

In Fig. 3 the general construction of the cut-out is the same as that shown in Figs. 1 and 2 but the valve stem, or lever, which is shown at 16, is somewhat differently arranged. As here shown, the valve stem extends downwardly from the valve and is then curved rearwardly and upwardly and is pivotally mounted on the body, at 17, and is provided with an upwardly extending arm 18 which may be connected with any suitable operating device. The shape of this lever and the arrangement of its axis are such that when the valve is opened it will be moved upwardly and rearwardly so that it will lie adjacent to the normal outlet opening of the body and thus tend to divert the exhaust gases toward the supplemental outlet. In this form of the device no locking 20 device is provided but the valve, which is shown at 19, is of such a size and weight that it will be held firmly in its closed position by gravity.

The operation of the cut-out will be 35 readily understood from the foregoing description and it will be apparent that I have provided a cut-out which is very simple and inexpensive in its construction, which can be very easily operated, and which is so constructed and arranged that both the valve and its seat are readily accessible for cleaning or other purposes. Further, by the use of a gravity valve I eliminate the use of springs, which are objectionable in a device 40 of this kind for various reasons, one reason being that the temper is drawn from the springs by the heat of the exhaust and they quickly lose their effectiveness. Further, the springs must be of considerable stiffness and 45 render the valve more or less difficult to operate. This construction also enables the operating device to be placed upon the dash instead of upon the foot board and when an operating cable is used this cable does not 50 need to be maintained taut as is necessary with an ordinary spring operated cut-out. Further, the valve has a relatively narrow 55 surface of contact on its valve seat and will thus seat itself in any deposits which may 60 accumulate upon the valve seat and there will be little or no tendency to leakage on the part of the valve, and, further, there will be little or no tendency of the valve to 65 stick in its seat. Moreover, I have provided the cut-out with a lock which will positively

hold the valve in its closed position and prevent the same from rattling or chattering under any condition of service. The whole device is of such a character that it can be quickly and easily applied to an exhaust pipe 70 and will require very little, if any, attention to maintain it in operative condition. Further, it will be apparent that the cut-out is of such a character that it can be clamped about the exhaust pipe without cutting the 75 same, as is customary in the applying of cut outs to exhaust pipes. The exhaust pipe is continuous through the body of the cut-out and is merely provided with an opening 80 which registers with the outlet opening of the cut-out. This results in a much stronger construction and one in which the parts are much less liable to loosen and rattle. It will also be noted that the valve is mounted on the body of the cut-out exteriorly thereof so that there are no pivot pins, or other parts, extending through the 85 walls of the exhaust line to loosen and leak.

While I have shown one embodiment of 90 my invention, and a minor modification thereof, I wish it to be understood that I do not desire to be limited to the details shown and described, as various modifications may occur to a person skilled in the art.

Having now fully described my invention 95 what I claim as new and desire to secure by Letters Patent, is:

1. In a device of the character described, a body adapted to be connected in the exhaust line of an internal combustion engine and having a supplemental outlet provided with a valve seat, a weighted valve arranged within said body and held in firm contact with said seat by gravity, a stem secured to 100 said valve, extending through said supplemental outlet and pivotally mounted exteriorly of said body and out of line with said supplemental outlet, and means acting on said stem to move said valve into its open position, said stem being arranged to move 105 said valve into a position in which it will extend transversely to said body and will direct a part of the exhaust gases toward said supplemental outlet. 110

2. In a device of the character described, a body adapted to be connected in the exhaust line of an internal combustion engine and having a supplemental outlet provided with a tapered valve seat, a tapered valve arranged in said body and held in firm contact with said tapered valve seat by gravity, a stem rigidly secured to said valve, extending through said supplemental outlet and pivotally mounted on the exterior of said body and out of line with said supplemental outlet, and means acting on said stem to move said valve into its open position, said stem being arranged to move said valve into a position in which it will extend transversely to said body and will direct a part 115 120 125 130

- of the exhaust gases toward said supplemental outlet.
3. In a device of the character described, a body adapted to be connected in the exhaust line of an internal combustion engine, said body having a part of the lower wall thereof depressed to form a valve seat terminating in a supplemental outlet, a weighted valve arranged within said body and held in firm contact with said valve seat by gravity, said depression being of such depth that said valve will be supported normally out of the path of the gases passing through said exhaust line, a stem secured to said valve, extending through said supplemental outlet and pivotally mounted exteriorly of said body and out of line with said supplemental outlet, and means acting on said stem to move said body into its open position, said stem being arranged to move said valve into a position in which it will extend transversely to said body and will direct a part of the exhaust gases toward said supplemental outlet.
4. The combination of a continuous exhaust pipe having an opening in one side thereof, a cut-out comprising a tubular body secured to said pipe and having an outlet adjacent to and registering with said opening, a gravity valve arranged within said body to normally close said outlet, said valve being arranged to enter said pipe and to extend transversely thereto when moved to its open position, and a stem secured to said valve and mounted on the exterior of said body and out of line with said outlet, and means for actuating said stem to move said valve into its open position.
5. In a device of the character described, a body portion adapted to be connected in the exhaust line of an internal combustion engine and having a supplemental outlet in its bottom wall, a gravity valve arranged within said body to normally close said supplemental outlet, said valve having a stem extending through said supplemental outlet to a point below the same, and thence upwardly and toward one end of said body, means for pivotally mounting said stem on a transverse axis on the exterior of said body, and means for actuating said stem to move said valve into its open position.
6. In a device of the character described, a body portion adapted to be connected in the exhaust line of an internal combustion engine and having a supplemental outlet in its bottom wall, a gravity valve arranged within said body to normally close said supplemental outlet, said valve having a stem extending through said supplemental outlet to a point below the same, and thence upwardly and toward one end of said body, means for pivotally mounting said stem on a transverse axis on the exterior of said body, and a cable connected with said stem for moving said valve to its open position.
7. In a device of the character described, a body portion adapted to be connected in the exhaust line of an internal combustion engine, and having a supplemental outlet in the bottom wall thereof, a downwardly converging flange leading from said bottom wall to said supplemental outlet, a gravity valve arranged within said body and adapted to engage said flange to close said supplemental outlet, a stem carrying said valve, extending through said supplemental outlet and movably mounted exteriorly of said body, and means for acting on said stem to move said valve into its open position.
8. In a device of the character described, a body adapted to be connected in the exhaust line of an internal combustion engine and having a supplemental outlet, a gravity valve arranged within said body to normally close said supplemental outlet, means for moving said valve into its open position, and a locking device to secure said valve in its closed position.
9. In a device of the character described, a body adapted to be connected in the exhaust line of an internal combustion engine and having a supplemental outlet, a gravity valve arranged within said body to normally close said supplemental outlet, means for moving said valve into its open position, and a gravity operated locking device to secure said valve in its closed position.
10. In a device of the character described, a body adapted to be connected in the exhaust line of an internal combustion engine and having a supplemental outlet, a gravity valve arranged within said body to normally close said supplemental outlet, said valve having a stem extending through said supplemental outlet and movably mounted exteriorly of said body, a locking device acting on the stem of said valve to hold the latter in its closed position, and means to release said locking device and move said valve into its open position.
11. In a device of the character described, a body adapted to be connected in the exhaust line of an internal combustion engine and having a supplemental outlet, a gravity valve arranged within said body to normally close said supplemental outlet, said valve having a stem extending through said supplemental outlet and movably mounted exteriorly of said body, a gravity operated locking device mounted on said body and having a part to engage said stem to hold said valve in its closed position, and having another part arranged to engage said stem after the first mentioned part has been moved into an inoperative position and move said valve to its open position, and an operating device connected with said locking device.

12. In a device of the character described, a body adapted to be connected in the exhaust line of an internal combustion engine and having a supplemental outlet, a gravity valve arranged within said body to normally close said supplemental outlet, said valve having a stem extending through said supplemental outlet and pivotally mounted exteriorly of said body, a locking device pivotally mounted on said body and having a part adapted to engage the upper portion of said pivoted valve stem to secure the valve in its closed position and having another part adapted to engage the lower side of said valve stem to move said valve into its open position, and means for actuating said locking device and said valve.

13. In a device of the character described, a body adapted to be connected in the exhaust line of an internal combustion engine having a supplemental outlet, a gravity valve arranged within said body to normally close said supplemental outlet, said valve having a stem extending through said supplemental outlet and pivotally mounted exteriorly of said body, a locking arm pivotally mounted on said body and having its outer end portion bifurcated, the bifurcated portions thereof extending on opposite sides of said valve stem, that part of said locking arm lying between the bifurcated portions thereof being arranged to engage said valve stem when said locking device moves downwardly by gravity, said locking arm also having a part extending beneath said valve stem and so arranged that it will not engage the valve stem until the first mentioned part of said locking arm has been moved into inoperative relation thereto, and an operating device connected with said locking arm.

stem when said locking device moves downwardly by gravity, and means for moving said locking device into an inoperative position and for moving said valve into its open position. 35

14. In a device of the character described, a body adapted to be connected in the exhaust line of an internal combustion engine having a supplemental outlet, a gravity valve arranged within said body to normally close said supplemental outlet, said valve having a stem extending through said supplemental outlet and pivotally mounted exteriorly of said body, a locking arm pivotally mounted on said body and having its outer end portion bifurcated, the bifurcated portions thereof extending on opposite sides of said valve stem, that part of 50 said locking arm lying between the bifurcated portions thereof being arranged to engage said valve stem when said locking device moves downwardly by gravity, said locking arm also having a part extending beneath said valve stem and so arranged 55 that it will not engage the valve stem until the first mentioned part of said locking arm has been moved into inoperative relation thereto, and an operating device connected 60 with said locking arm.

In testimony whereof, I affix my signature hereto.

HARRY W. RUBY.
